United States Patent Office.

GEORGE N. CREAMER, OF TRENTON, NEW JERSEY, ASSIGNOR TO HIMSELF
AND JOHN B. LALOR, OF SAME PLACE.

Letters Patent No. 78,265, dated May 26, 1868.

IMPROVED SAFETY-HATCH.

The Schedule referred to in these Letters Patent and making part of the same.

TO ALL WHOM IT MAY CONCERN:

Be it known that I, GEORGE N. CREAMER, of Trenton, in the county of Mercer, in the State of New Jersey, have invented a new and improved Safety-Hatch to be used by merchants and others; and I do hereby declare that the following is a full and exact description thereof, reference being had to the accompanying drawings, and to the letters of reference marked thereon.

The nature of my invention consists in the construction of a hatch to be used in warehouses, ships, and other places where it is necessary to have openings in floors, for the removal of merchandise, freight, and other goods from one floor to another, said hatch to be self-closing, and to be opened by a person standing any number of stories above or below the floor, the hatch of which is required to be opened.

To enable others skilled in the art to make and use my invention, I will proceed to describe its construction and operation.

I construct my hatch of any size to suit the size of the opening through the floor through which the merchandise is required to pass, I construct it either in one single door or carriage, moving to one side of the hatchway, where the same is to be opened, or in two doors or carriages, separating in the middle, and, when opening the hatchway, the carriages to move in opposite directions, one to each side of the hatchway.

In Figure 1, in the accompanying drawings, a top plan or view of the hatch closed is shown. The letters *a a* designate the two halves of the hatch; *c e*, the railway, upon which the hatch runs; *d d*, the rods, to which the cords are attached, which open and close the hatchway; *f f*, two cords, which open the hatchway; *i i*, two cords, which come together at or near the hand operating the hatch; *j j*, two levers, acting as locks, by the lighter ends rising up against the rear ends of the carriages when they are closed, in order to prevent them from moving accidentally when some one might be standing upon them; *k k k k* are four pulleys, through which the ropes or cords render; *m* is the rope or cable, used to raise the merchandise, it hanging in an opening designed for it when the hatch is closed, by small blocks which prevent the hatch-carriages from coming together too closely.

Figure 2 is a side elevation of the double hatch with hatchway closed, showing very fully the workings of the machine. *A A* are the two hatch-carriages, closing the hatchway; *B B B B* are the wheels upon one side of the carriages, upon which the same run; *C* is the railway; *D D* the rods, to which the ropes are fastened, which operate the carriages; *E E*, two weights, which draw the carriages apart, by means of the ropes *F F*, thus opening the hatchway; *G G*, two weights, which, by the cords *H H*, close the hatchway; *I I I*, cords, operated upon by the hand of the person desiring to open the hatchway, which end is accomplished by raising the weights *G G*. *J J* are two levers, which lock the hatch when closed, by reason of the ends *J J* being the heavier, and throwing the other ends up in the rear of the carriages. *K K K K K K K* are seven pulleys, through which the ropes render, which are required to operate the hatch. *l l* are two rods, the upper ends of which are fastened in the levers *J J*, and made to work in a slot, in order to allow the small ends of said levers to work up and down freely. At the lower ends of said rods are two pulleys, through which the hand-ropes pass, so that when the pressure is applied to these ropes, the rods *l l* are pulled down, bringing the light ends of the levers *J J* with them, thus unlocking the carriages, and the same pull of the said ropes elevating weights *G G*, in doing which the counterbalancing weights to weights *E E* are removed, allowing these latter weights to instantly open the hatchway by drawing back the carriages. *m* is the rope, by which the merchandise is lifted; *n* is the joist in the flooring; *o o* are two slots in which the rods *l l* work; *P P* are the pins or hinges, upon which the levers *J J* work; *Q* is the hand applied to the hatch-rope. This rope may be carried to the entire height and depth of the building, in order that a person upon any floor of the building can control the hatch.

Figure 3 is also a side elevation of the hatch open, but instead of the hatch being divided, as in fig. 2, it consists of but one carriage. *a* is the hatch-carriage; *b b* are the wheels on one side of the carriage; *c* is the railway, upon which the carriage runs; *d* is the rod, to which the ropes used in opening and closing the hatch are attached; *e* is the weight which draws back the carriage, thus opening the hatchway, as seen in this draw-

ing, the hatchway in this figure being open; *f* is the rope connecting the weight *e* with the rod *d*; *g* is the weight which closes the hatchway, upon the hand or power being removed from the rope *i*; *J* is the locking-lever, which holds the carriage firmly to its place when closed; *k k k* are four pulleys, over which the ropes or cords pass; *l* is a rod, connecting at the upper end with the lever *J*. At the lower end is a pulley, over which the hand-rope passes. When the hand-rope is pulled, the rod *l* is drawn down, thus causing the lever *J* to unlock, allowing the carriage to run back and open the hatchway. *n* is the joist in the flooring; *o* is the slot in which the rod *l* works; *p* is the hinge, upon which the lever *J* works; *q* is the hand-rope, used in opening the hatchway.

By an examination of the forces brought to bear in the operation of the hatch, it will be seen that in case the hand-rope should be drawn, (which opens the hatchway,) while a person or any article of freight is upon the hatch-carriages, the same will not open until said weight is removed, so that nothing which may be on the hatch at any time, can be thrown down by a person operating upon the hatch from a distant part of the building.

The reason of this is obvious, viz, the weights *E E*, in fig. 2, are of just sufficient weight to draw the carriages when the same are unloaded, so that a weight, however small, which is upon either carriage, will throw the balance of power in favor of the carriage, and it will fail to move or respond to the operator on the hatch-rope, so long as the weight remains there.

What I claim as my invention, and desire to secure by Letters Patent, is—

1. The construction and arrangement of hatchways, when operated in the manner and for the purpose herein described.
2. The combination of the hatch-carriages *A A*, levers *J*, weights *C*, cords *I*, and pulleys *k*, in the manner and for the purpose herein described.
3. The locking-device or levers *J*, in combination with the truck or carriage *A A*, in the manner and for the purpose herein described.

GEORGE N. CREAMER.
